CLAIM

The ornamental design for a manicure support stand, as shown and described.

DESCRIPTION

FIG. 1 is a front isometric view of my manicure support stand;

FIG. 2 is a rear isometric view thereof;

FIG. 3 is a top plan view thereof;

FIG. 4 is a front elevational view thereof;

FIG. 5 is a side elevational view thereof, the opposite side being a mirror image;

FIG. 6 is a rear elevational view thereof;

FIG. 7 is a bottom plan thereof; and,

FIG. 8 is a side elevational view on an enlarged scale, showing portions partially broken away and in section for clarity and completeness of disclosure.
